UNITED STATES PATENT OFFICE.

WILLIAM J. KEMPER, OF COVINGTON, KENTUCKY.

DOOR-CONTROLLING MEANS.

Application filed June 22, 1923. Serial No. 647,157.

To all whom it may concern:

Be it known that I, WILLIAM J. KEMPER, a citizen of the United States, residing at Covington, in the county of Kenton and

5 State of Kentucky, have invented certain new and useful Improvements in Door-Controlling Means, of which the following is a specification.

10 My invention relates to means for controlling doors and is exemplified in connection with garage doors for locking the same and for holding the same in various open positions.

15 It is the object of my invention to provide a simple, effective and strong device for locking a closure such as a door and for holding the same in a definite open position; further, to provide improved door controlling means whereby the door may be 20 held in locked closed relation or in locked open relation, and whereby release in the controlling means permits the swinging of the door through an angle of substantially one hundred and eighty degrees.

25 The invention will be further readily understood from the following description and claims, and from the drawings, in which latter:

30 Fig. 1 is an inside elevation showing my improved device applied to a pair of doors.

Fig. 2 is a horizontal cross-section taken on the line 2—2 of Fig. 1, partly broken away, showing the doors in closed relation in full lines and one of the doors in locked 35 open relation in dotted lines.

Fig. 3 is a horizontal cross-section taken on the line 2—2 of Fig. 1, partly broken away, showing the doors in closed relation in full lines and one of the doors shown in 40 dotted lines with its controlling means in release relation and swung into full open relation.

Fig. 4 is a front elevation of my improved controlling means.

45 Fig. 5 is a plan view of the same.

Fig. 6 is a horizontal section of the same, taken on the line 6—6 of Fig. 4.

Fig. 7 is a detail in horizontal section, taken on the line 6—6 of Fig. 4, partly 50 broken away, and showing the bolt in release relation.

Fig. 8 is an end view of the same; and,

Fig. 9 is a detail in cross-section taken on the line 9—9 of Fig. 5.

55 I have in Figs. 1 to 3 shown my improved device applied to a pair of doors arranged

to swing outwardly to the right and left for providing full clearance for the door-opening.

My improved device is shown in these 60 figures as applied to a right hand door and to a left hand door, the various parts of this device being, however, designated by similar reference numerals, so that a description of one of the devices will serve for the pair 65 of the same.

The doors are shown at 11 and 12, forming closure for a door-opening 13, the walls of which are shown at 14. The doors are hinged by means of hinges 15, of suitable 70 number and suitably placed, so as to swing outwardly in order that the inside of the garage may be clear of the doors.

Each of the doors is provided with a guide-strip 18, the guiding portion 19 of 75 which is spaced from the door by a space 20, by means of brackets 21 at the ends of the guide-strip, terminating in feet 22 secured against the inside face of the door, as by means of screws 23.

80 A brace-rod 25 is hinged to the wall of the door-opening by means of a hinge 26, having a removable pintle 27, held to the brace-rod by means of a flexible connection, shown as a chain 28, one end of which is secured in a hole 29 in the brace-rod and the other end of which is fastened in a ring 30 on the removable pintle. The removable pintle is received through eyes 31 formed by bending the end of the brace-rod and 85 through an eye 32 of a member 33 of the hinge arranged to be secured to the wall of the door-opening. The eyes 31 are separated by a slot 34 in the end of the brace-rod, the eye 32 being received in said slot. 90

95 The swinging end of the brace-rod is at its upper and lower edges provided with flanges 41, 42, for forming slots 43, 44, in which the guide-strip is received. The swinging end of the brace-rod is also provided with an outward bulge 45 between said flanges whereby to additionally strengthen said swinging end.

100 The flanges are received about the upper and lower edges of the guide-strip, for locating said upper and lower edges in said slots. The outer bracket of the guide-strip is provided with notches 46, 47, through which the flanges 41, 42, may be readily received when 105 assembling the parts, for locating the 110 guide-edges of the guide-strip in the edge slots of the swinging end of the brace-rod,

A spring 51 has its inner end secured to the brace-rod, for instance, by means of rivets 52. It is provided with an outward bend 53 intermediate of its ends, so that its outer portion is located at the outer face of the bulge 45, the outer end of said spring being provided with a handle 54, shown as an outer curled end of said spring. A bolt 55 is fixed to the outer end of said spring, as by means of a screw 56. The bolt is received through a hole 58 in the bulge 45.

The guide-strip is provided with holes 61, 62, adjacent the brackets, the bolt being arranged to be selectively received in said holes. When the bolt is located in the outer hole, the door is in locked closed position, as shown in Fig. 1 and in full lines in Figs. 2 and 3.

If it is desired to open the door, the bolt 20 is withdrawn from the hole 61 by pulling on the handle 54, whereupon the door may be swung outwardly and the guide-strip slide in the guideway in the swinging end of the brace-rod. When the door has been swung outwardly as shown in dotted lines in Fig. 2, the bolt snaps into the hole 62 and locks the door in open relation.

The bolt swings with the outer end of the spring on an arc having the fixed end of the spring as a pivot, and the relation of the bolt and the hole 58 in the bulge 45 is such, that when the bolt has been sufficiently withdrawn to be clear of the hole in the guide-strip, the side of the bolt contacts the wall of the hole 45 in the bulge, and thereby prevents further outward movement of the spring for maintaining the bolt in the hole 58, and permits the handle 54 to be used as a handle for swinging the door, and for opening and closing the same, and for locking the same in open position or in closed position. This insures that the parts are maintained in operative relation so that when the door is swung outwardly to open the door or inwardly to close the door, the bolt will automatically snap into the corresponding hole in the guide-strip for automatically locking the door either in open relation or in closed relation.

It will be noted from Fig. 2 that the construction is such, further, that by comparatively small movement between the swinging end of the brace-rod and the guide-strip, the door may be swung from closed relation through an arc greater than ninety degrees, to a position at substantial right angles to the plane of the door-opening, for full clearance of the door-opening. If it is desired to swing the door to greater extent so that the door is substantially against the outer face of the wall of the garage, the pintle 27 may be withdrawn from the hinge, and the swinging of the door continued throughout an arc of substantially one hundred and eighty degrees, as shown in dotted lines in

Fig. 3, so as to be substantially parallel with the plane of the door-opening.

The bolt connection and the flange connection between the swinging end of the brace-rod and the guide-strip is such as 70 to insure maintenance of connection between them, so that when the door is swung back into substantially right angle position with relation to the door-opening, the pintle may again be inserted into the eyes of the 75 hinge for again readily connecting the parts.

My improved construction is simple and strong and takes up little space, and is out of the way when in use, and insures the locking of the door from the inside, all of the 80 operating parts of the device being on the inside of the door when the door is in closed position. The brace-rod and the guide-strip may be formed out of flat metal and are of simple construction. The device 85 provides ready means for locking the door either in closed relation or in full open relation, as shown in Fig. 2.

Having thus fully described my invention, what I claim as new, and desire to secure by Letters Patent, is:

1. The combination, with a door and a wall of the door-opening, of a brace-rod pivoted at one end to said wall, a guide-strip secured to said door and provided with holes, the swinging end of said brace-rod provided with flanges about said guide-strip for sliding connection therewith and with an outward bulge intermediate between said flanges, said outward bulge provided with a hole, a spring-bar, means rigidly securing one end of said spring-bar to said brace-rod in manner to permit swinging of the other end of said spring-bar on said brace-rod, the swinging end of said spring-bar formed with a handle, and a bolt fixed to the swinging end of said spring-bar and operating in said hole in said bulge and arranged to be received in said holes in said guide-strip, said bolt arranged to wedge against the wall 100 of said hole in said outward bulge for limiting the outward swinging movement of said swinging end of said spring-bar for constituting said handle as a handle for moving said door.

2. The combination with the wall of a door-opening, a door pivoted to said wall on a hinge having a pintle at the outer side of said wall and laterally spaced from the edge face of said wall and arranged for outward 120 swinging of said door, a brace-rod pivoted at one end to said wall closely adjacent to said edge face at the inside of said door, a guide-strip secured to the inner face of said door and provided with holes, said brace-rod and guide-strip located in the median portion of the height of said door, the swinging end of said brace-rod provided with flanges about said guide-strip for sliding connection therewith, a spring-bar, one end 125

of which is fixed to said brace-rod adjacent to its swinging end, the other end of said spring-bar arranged to swing toward and from the swinging end of said brace-rod, 5 said spring-bar provided with a handle, and a bolt on said spring-bar received through said brace-rod and arranged to be received in said holes in said guide-strip for positioning said door, and constructed and arranged whereby said brace-rod is maintained at the 10 inside face of said door and substantially parallel with the plane of said door throughout the swinging movements of said door, and whereby said door is swung outwardly 15 and said door-opening is cleared of substantially all of said brace-rod and its connections when said door is open.

3. The combination with the wall of a 20 door-opening, a door pivoted to said wall on a hinge having a pintle at the outer side of said wall and laterally spaced from the edge face of said wall and arranged for outward swinging of said door, a brace-rod pivoted at one end to said wall closely adjacent to 25 said edge face at the inside of said door, a guide-strip secured to the inner face of said door and provided with holes, said brace-rod and guide-strip located in the median portion of the height of said door, the swinging 30 end of said brace-rod provided with flanges

about said guide-strip for sliding connection therewith, a spring-bar, one end of which is fixed to said brace-rod adjacent to its swinging end, the other end of said spring-bar arranged to swing toward and from the swinging end of said brace-rod, 35 said spring-bar provided with a handle, and a bolt on said spring-bar received through said brace-rod and arranged to be received in said holes in said guide-strip for positioning said door, constructed and arranged whereby said door is swung outwardly and said brace-rod is maintained substantially parallel with the plane of said door throughout the swinging movements of said door, 40 and the pivotal connection between said brace-rod and said wall of said door-opening comprising a removable pintle for swinging said door outwardly to greater extent than the open locked relation between said wall 45 and said door during maintenance of said pivotal connection.

In testimony whereof, I have hereunto signed my name in the presence of two subscribing witnesses.

WILLIAM J. KEMPER.
